UNITED STATES PATENT OFFICE.

HUBERT F. KRANTZ, OF BROOKLYN, NEW YORK, ASSIGNOR TO KRANTZ MANUFACTURING COMPANY, INC., OF BROOKLYN, NEW YORK, A CORPORATION OF NEW YORK.

SWITCH-PANEL.

1,306,342.

Specification of Letters Patent. **Patented June 10, 1919.**

Application filed March 10, 1916. Serial No. 83,247.

To all whom it may concern:

Be it known that I, HUBERT F. KRANTZ, a citizen of the United States, and residing at Brooklyn, in the county of Kings and State 5 of New York, have invented a new and Improved Switch-Panel, of which the following specification is a full disclosure.

This invention deals with switch-boards, and it proposes a very simple and compact 10 switch-mechanism of the type especially adapted for panel-boxes and the like.

A primary object is to create a switch-board in which as few parts as possible 15 can be used while yet affording every facility of operation and every degree of safety in point of usage.

A further purpose of this invention is to provide a simple switch-system affording a direct connection from a bus-bar to 20 a branch-line terminal by the use of a single switch-element and without necessitating the employment of a multiplicity of contact-elements.

Other objects will be in part obvious 25 from the annexed drawings and in part indicated in connection therewith by the following analysis of this invention.

This invention accordingly consists in the features of construction, combinations of 30 parts, and in the unique relations of the members and in the relative proportioning and disposition thereof; all as more completely outlined herein.

To enable others skilled in the art so 35 fully to comprehend the underlying features thereof that they may embody the same by the numerous modifications in structure and relation contemplated by this invention, drawings depicting a preferred 40 form have been annexed as a part of this disclosure, and in such drawings, like characters of reference denote corresponding parts throughout all the views of which:—

45 Figure 1 is a plan view of a panel-box embodying this invention, and showing the method of application whereby branch-line circuits may derive current from main bus-bars. Fig. 2 is a longitudinal section 50 of Fig. 1 and Fig. 3 is an external plan of the box; Fig. 4 being a detail. In the drawings A indicates a base-board of insulating material which, together with the side-walls, B and C form a box or basin. 55 Within this box are arranged a series of parallel bus-bars X, Y and Z which are above the bottom so as to overlie the cross-bars *x*, *y* and *z* with which they are respectively connected. These cross-bars lie on the base-board A and terminate in proximity with the switch-blades 1, 2 and 3; 60 preferably consisting of a plurality of copper laminations arranged in echelon as shown and adapted to be rotated about the axis 4. Branch-line terminals D, E and F are arranged on one side of the base-board A in opposition with the respective cross-bars *x*, *y* and *z*, and these branch-line terminals provide contact-portions *d*, *e*, and *f*, which lie in an upper plane diagonally opposite the contact-portions of the cross-bars *x*, *y* and *z* so that the switch-blades 1, 2 and 3 may establish electrical connection diagonally across the intervening space. 70

The switch-mechanism is mounted directly on the base-board A, as by means of the side-standards 5 and 6, and the pivot extensions 4 of the switch-blades are pivoted in these side-standards, and a spring 7 is arranged so as normally to urge the switch-blades 1, 2 and 3 into their open-circuit positions. By means of a handle G the mechanism may be set to lock the switch-blades diagonally into direct contact with the branch-line terminals and the cross-bars, 75 respectively; preferably by means of a toggle-mechanism forming a component part of the switch-mechanism. Thus, the handle is secured to a swinging yoke 8, which is carried by the pivots 9 and 10 mounted 80 on the standards 5 and 6. This yoke also provides an arm 11 which provides a pin 12 in its outer end, and this pin in turn actuates a bell-crank 13 also mounted on the pivot 10. A toggle link 16 is also mounted 85 by one of its ends upon the pivot 10 and is connected at its opposite end by a pivot pin 17 to a second toggle link 14 which in turn is connected with the actuating arm 15 of the switch-blade proper. This switch-mechanism is substantially the same as that 90 described in my copending application No. 42,956 filed July 31, 1915. The bell-crank 13 provides opposing spaced shoulders 18 and 19 arranged to engage the knee of the 95 toggle to throw the toggle into either of its extreme positions, the space between the shoulders providing the necessary lost motion whereby to enable the toggle to shift freely. Any suitable means may be em- 100 105 110

- ployed for limiting the movements of the toggle, as for instance, the standard 6 may be provided with an arcuate slot 19, as indicated by the dotted lines in Fig. 4, said 5 slot being positioned to receive a portion of the pin 17. Engagement of the pin against the opposite end walls of the slot will determine the limits of movement of the toggle.
- 10 It will be observed that this switch-mechanism as a whole is supported on the base-board A and that the same is covered entirely, including all live parts, by means of a cover-plate H thereby creating a very 15 safe organization.
- Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore, such adaptations should 20 and are intended to be comprehended within the meaning and range of equivalency of the following claims.
- Having thus revealed this invention, I claim as new and desire to secure the following combinations of elements, or equivalents thereof, by Letters Patent of the 25 United States:
1. A panel box made up of top, bottom and side walls defining an inclosure, a bus 30 bar mounted upon the bottom wall within the inclosure, a branch line terminal member also mounted upon the bottom wall within the inclosure and having a portion extending upwardly from the bottom wall 35 terminating in a contact part spaced upwardly from said bottom wall and from said bus bar, a pair of standards also supported by said bottom wall and projecting upwardly therefrom within the inclosure, a 40 switch blade carrier pivotally mounted by said standards upon an axis substantially parallel with said bottom wall and in a plane intermediate the bus bar and said contact, a switch blade connected with said carrier having a pair of contact portions projecting laterally in opposite directions from the pivotal axis of the carrier adapted when the carrier swings to engage the bus bar and said first contact respectively, and 45
- means projecting through the top wall of the inclosure to a position of accessibility for swinging said switch blade and carrier at will. 55
2. A switch mechanism combining a casing, a bus bar arranged within the casing, extending along one wall thereof, a pair of independently operable switch mechanisms arranged within the casing one adjacent each of the opposite ends of the bus bar and being spaced apart to provide an open space 60 between them, a main line feeder extending into said open space and being connected with the bus bar intermediate the ends of the bus bar, a pair of branch line terminals one adjacent each end of the bus bar, said 65 branch line terminals being supported by the mentioned wall of the casing but having portions extending away from said wall and terminating in contact parts spaced diagonally from the respective adjacent end portions of the bus bar, each of said switch mechanisms including a switch blade operable to close circuit between the bus bar and the adjacent branch line terminal, and an operating handle for each switch mechanism 70 projecting through another wall of the casing to a position of accessibility exteriorly of the casing. 75
3. A switch panel comprising a box made up of top, bottom and side walls, a bus bar 85 lying upon the bottom wall within the box, a branch line terminal member mounted upon the bottom wall within the box and having a portion bent upwardly from said bottom wall terminating in a contact part 90 spaced upwardly from the bottom wall and from said bus bar, a switch blade, and operating means therefor extending through the top wall, said switch blade being double ended and being pivotally supported at its 95 mid portion adapted to swing one of its ends toward the bottom wall into engagement with the bus bar and its opposite end away from the bottom wall into engagement with the branch line contact. 100

In witness whereof, I hereunto subscribe my name, as attested by the two subscribing witnesses.

HUBERT F. KRANTZ.
